CERTIFICATE OF CORRECTION

PATENT NO. : Des. 521,304 S
APPLICATION NO. : 29/220678
DATED : May 23, 2006
INVENTOR(S) : Joseph Mandel

Page 1 of 7

It is certified that error appears in the above-identified patent and that said Letters Patent is hereby corrected as shown below:

The title page showing an illustrative Figure should be deleted and substitute therefore the attached title page consisting of Figure 1.

The attached formal drawing containing FIGS. 1-6 is substituted for the FIGS. 1-6 printed in the patent.

Signed and Sealed this

Thirteenth Day of February, 2007

A handwritten signature in black ink, appearing to read "Jon W. Dudas", is centered on a dotted rectangular background.
